UNITED STATES PATENT OFFICE

2,545,973

SUPPORTING MEMBER FOR PULL CHAIN SWITCHES

Benjamin Schoenberg, Corona, N. Y.

Application April 17, 1948, Serial No. 21,597

2 Claims. (Cl. 248—343)

1

My invention is an improvement in supporting members for electric switches; especially switches of the pull-chain type for lighting fixtures and other electrical appliances.

An important object of my improvement is to provide a member adapted to be easily attached adjacent a lighting fixture, so that the switch can be securely mounted; with the chain or cord hanging down within easy reach of one's hand to actuate the switch and thus turn on the light or extinguish it.

Another object is to provide a member of this kind so constructed that the chain or the like is always maintained in the most efficient operating position. To this end the casing of the switch is adjustably connected to the supporting member or fitting.

The nature, objects and advantages of the invention are set out in the following description and accompanying drawings and the novel features are defined in the appended claims.

On the drawings:

Figure 1 is a front view, partly in section, of a device for use with a lighting fixture, secured to a ceiling or the like, with my improvement thereon.

Figure 2 is a perspective view of the supporting member or fitting.

Figure 3 is a section on line 3—3 of Figure 2.

Figure 4 shows a modification; and

Figure 5 shows another modification.

The numeral 1 indicates part of an outlet device having a downward extending boss or neck 2. This device is affixed to the ceiling of a room, for example; or any other suitable place; and is associated with the fixture having the usual sockets, not shown, for electric lamps. The boss or neck 2 is hollow and is adapted to give passage to electric conductors which are led out through it and connected to the lamps or other devices which are to be energized. The outlet device 1 and the fixture are not parts of this invention and a fuller description thereof is not required.

On the boss or neck 2 is screwed a supporting member or fitting 3, that engages threads 4 on the lower end of the boss 2. The member 3 carries the casing 5 containing the parts of the switch, and the latter is of course put into the circuit of the electric wiring to the lamps. The mechanism of the switch is well known and need not be further illustrated. It is actuated by a pull chain or cord 6, passing out from the inside of the casing through the lower end of the member 3. Switches of this kind are very de-

2

sirable for electric lighting fixtures; because they are easy to operate but it has always been difficult to mount them properly to give the service required of them. The aim of my invention is to provide means for conveniently doing this. The chain or cord 6 is enclosed in a guide tube or sleeve 7 made fast to the fitting 3, this sleeve extending down far enough to make sure that the element 6 will not bind against or foul with any part of the outlet device or lighting fixture adjacent the device 1.

The mode of mounting the casing 5 is illustrated particularly in Figures 1, 2 and 3, the first of these views presenting the switch casing at 15 one side of the member 3. The general shape of this member or fitting is that of a U turned over on its side. It comprises a body having at the top a securing part such as a large ring 8, with internal threads to enable the fitting to 20 be screwed upon the neck 4. The opposite end carries a similar part in the form of a smaller ring 9, with internal threads to be engaged by threads on the upper end of the tubular extension or guide 7; the two rings 8 and 9 being substantially parallel and connected at one side by a bridge 10. The casing 5 is adjustably mounted on the lower part of the fitting 3 and when this fitting with the guide 7 joined thereto is 25 screwed upon the boss 2, the casing is securely mounted and smooth and certain operation of the switch is assured.

To this end the ring or part 9 has a lateral projection 11 on which is adjustably disposed an angle-shaped bracket 12 by which the casing 5 is held in position. One leg 13 of the bracket has arms or clips 14 which embrace the side edges of the projection 11; and the latter has a central slot 15. This leg 13 of the bracket has a threaded opening for a screw 16, which lies in the slot 15, and the head thereof, when the screw is tightened, presses against the lower face of the projection 11 and makes the bracket 12 fast. The other leg 17 of the bracket is vertical and has a threaded opening 18 into which the threaded neck 19 of the casing 5 is inserted. A binding nut 20 on the neck locks the casing to the bracket; and the casing has a tubular outlet 21 with a flaring end mouth 22 for the chain 6. The outer end of the mouth 22 is substantially over the center of the guide 7. The chain 6 can therefore always be pulled safely, because it slides smoothly in the flaring curved mouth 22 of the outlet 21.

In Figure 4, the bracket 12a has an opening 55 18 as before for the neck of the casing 5, but the

other leg 11a has a slot 15a and a screw 16 is employed to secure the bracket to the bridge 10; the latter having a threaded opening for this screw. This bracket also will bear the casing 5 in such position that the outlet 21 will hold the chain directly over the center of the extension 7.

Figure 5 shows the bracket 12b integral with the member. The projection 11b at one side of the lower ring 9 is in one piece with the ring and the leg 11b that has the threaded opening 18 for the tubular outlet 21 of the casing 5. The axis of this opening, as in Figures 1, 2, 3 and 4 will intersect the axis of the opening in the ring 9, and when the casing 5 is properly secured in the opening 18 the end of the tubular outlet 21 will again be directly over the center of the guide 7.

The member or fitting is thus quite simple, easy to mount and well adapted to serve the intended purpose.

While the embodiments above set forth are the preferred forms of my improvement I do not wish to be restricted thereto in all details, but I reserve the right to make changes without deviating from the general design that distinguishes the invention.

Having described my invention, what I believe to be new is:

1. A supporting member comprising a body having a ring at one end with internal threads, a ring at the other end with internal threads, said rings being substantially parallel, a bridge connecting said rings at the edges, a laterally extending bracket on said body, the bracket hav-

ing a leg with an opening the axis of which intersects the axis of said rings, said opening receiving the neck of a switch casing with a tubular outlet having its outer end substantially in line with the middle of the opening of the last-named ring.

5 2. A supporting member comprising a body having a ring at one end with internal threads, a smaller ring at the other end with internal threads, said rings being substantially parallel, 10 a bridge connecting said rings at the edges, a laterally extending bracket on said body, the bracket having a leg with an opening the axis of which intersects the axis of said rings, said opening receiving the neck of a switch casing with a tubular outlet having its outer end substantially in line with the middle of the opening of the last-named ring, said smaller ring at the other end having a slotted projection and said bracket having a second leg at an angle to the first with arms to engage said projection, and a screw in said slot to hold the bracket in adjusted position.
